VENDING DEVICE

Anthony Kuhn, New York, N. Y., and Charles H. Heitman, Bergen County, N. J.; said Heitman assignor to Andrew D. Reid, Weehawken, N. J.

Application July 26, 1930, Serial No. 470,826

5 Claims. (Cl. 312—36)

This invention relates to improvements in vending devices, being particularly directed to a vending mechanism applied in conjunction with a refrigerating device in a display casing, where- 5 by bottled goods may be disposed for sale in a manner so as to be easily removable from said display casing, in sequential or progressive order, without exposing the surfaces of the bottles to any undue shock, to cause breakage of the same 10 in their passage through the vending mechanism.

Broadly, it is an object of this invention to provide for a vending mechanism, in conjunction with a refrigerating unit, whereby bottled goods 15 may be caused to be progressively actuated and displaced from position in a storage receptacle in a display casing, while under the effect of the cooling medium controlled by the refrigerating mechanism, the bottled goods being caused to be 20 displaced in an angular and tortuous path, and in a manner so that the bottles reverse their direction of rotation after each and every angularly downward displacement and directional movement, for each of the several angular pas- 25 sages disposed in the storage receptacle.

Still further, it is an object of this invention to provide for a novel vending mechanism, in association with a refrigerating device, wherein the cooled bottled goods are caused to rest against 30 and move along stamped curved guide members defined so as to form a zig-zag tortuous passage, the said guide means being in the form of inverted V-shaped stampings, opposite stampings being disposed so as to provide a space slightly 35 larger than the diameter of a bottle, and the apex or ledge of the respective opposite guide means being disposed directly opposite to the flat portion of the opposite guide means.

Still further, it is aimed to provide a novel dis- 40 charging mechanism for refrigerated bottled goods, which have passed through a tortuous path in their progressive movement through the stor- age receptacle, which discharging mechanism comprises a shell formed of substantially one 45 cylinder within another, and having a cutout portion adapted to receive one and only one bot- tle, which said discharging mechanism is rotat- able upon the actuation of a control against spring tension to discharge the captured bottle 50 into the discharge opening, but at the same time, which is so disposed as to prevent the escape of cold air from the vending chamber as the dis- charging mechanism is rotated from point to point, and the downward movement of any bot- 55 tle in the storage receptacle, unless and until the

shell is empty, and disposed in a position to cap- ture another bottle.

Other objects and advantages, capabilities, and features of the invention will appear from the subjoined detailed description of one specific em- 60 bodiment of the invention as illustrated in the accompanying drawing, in which

Figure 1 is a front view, partly in section, of the completely assembled device.

Figure 2 is a plan view partly cut out of the 65 device.

Figure 3 is a side elevation in section along lines 3—3 of Figure 1.

Figure 4 is a plan view in section along lines 70 4—4 of Figure 3.

Figure 5 is a front view in section along lines 5—5 of Figure 3.

Referring to the reference characters in the drawing, numeral 10 represents a casing formed of stamped metal, and adapted to enclose the 75 vending chamber 11, or the distributing chamber 12, the freezing chamber 13, and the cooling chamber 14. The casing 10 has walls 15, carrying the usual form of insulation applied in refriger- 80

Since the wall structure, the brine or cooling chamber, and the electrical freezing unit are of the type normally used in electrical refrigerators, no description will be made of the same, nor will any detailed drawing of the same be shown herein, 85 except insofar as their location in relation to the elements forming the subject-matter of this invention.

Referring particularly to Figures 1 and 2, the vending chamber 11 comprises a series of sec- 90 tions 16, separated from one another and from the brine chamber respectively by metallic con- ducting walls 17 and 17', and extending from the top of the casing to the discharge chamber 12, there being provided a closure element 18 for the 95 top of the respective sections, and a discharging mechanism 19, which will be later described, such mechanism being adapted to serve as a closure for the lowermost portion of the respective sec- tions in conjunction with its operative functions. 100

Within each section 16, there is fastened to the respective walls 17 thereof, as by welding, riveting, or otherwise, a series of V-notched sections 20, so arranged along the respective walls as to form areas of depression 21, and areas of pro- 105 jection as ledges or ribs 22. As is clearly shown in Figure 1, the series of V-notched elements on the respective walls 17 of the sections 16 are so disposed that the ledges 22 and the depressions 21 on one wall are oppositely disposed respectively 110

to the depressions 21 and the ledges 22 on the other wall, that is, the apex of one element on one wall is directly opposite to the depression of the element on the other wall of the chamber.

5 Referring to Figures 3 to 5 inclusive, and with respect to the discharge mechanism, numeral 23 represents a knob formed integral with stub-shaft 24, having an arm 25, one end of which is attached to spring 26, the other free end of which is fixed 10 as at 27 to the wall of the casing. The shaft 24 passes through the wall 15 of the casing, and has fixed thereto the two-part double shelled discharge element 28, which discharge element comprises a plurality of concentric cylindrical shells 15 28 and 28', of a peripheral surface of more than 180 degrees, and a cutout portion 29, of area sufficient 20 to allow passage therethrough of a bottle, which extends from front to rear of the respective sections, and are mounted within the respective front wall of the casing and the wall 17' between the vending chambers and the cooling chamber, so that rotative movement of the same may be readily carried out. The inner surface of the inner concentric shell is of such cross-section as 25 to accommodate a beverage bottle 30 therein (see dotted line of Figure 4).

To prevent loss of cooling media, or waste of heat in the vending chamber, the inlet closure element 18 is formed of proper insulating material, and a plurality of ledges 31 and 31' are formed at the side of each of the respective discharging shells, so as to form both a bearing surface therefor, in conjunction with the end bearing surface therefor previously described, and at 30 the same time, prevent loss of cooling media.

As shown in Figures 1, 3, and 5, the beverage bottle 30 is inserted into one of the sections, as by means of the inlet thereof, and is then caused to assume a serpentine or tortuous path (see the 40 cross-sectional view in Figure 1), the respective bottles being caused to reverse their direction of rotation as they impinge on the respective ledges 22 of the V-shaped elements on the opposite walls of the vending sections (see arrows in Figure 1).

45 In normal operation, one beverage bottle rests within the inner shell 28' of the discharge member (see the right-hand side of Figure 5) so that the remaining beverage bottles are disposed thereabove in the position shown in the cross-sectional view in Figure 1. When and as a beverage bottle is desired to be sold, the knob 23 is turned to the left (see the arrows in Figure 1), causing the shell to be displaced about its bearing surface formed by the ledges 31, so that the beverage bottle drops out from the opening 29 onto the felt layer 32 in the base of the discharge chamber. Up to this point, and during this operation, the bottles remain in their position shown in Figure 1, since the outer peripheral surface of shell 28' presses against the bottle disposed thereabove; however, when the knob 23 is rotated or caused to be rotated in reverse to the direction of original rotation, so that the opening 29 in the discharge unit is disposed directly under the bottle carried on the last ledge (see the left-hand side of Figure 5), the bottle in such position then drops into the discharging mechanism against the inner shell 28' and remains there awaiting discharge at the will of the vendor.

70 Spring member 27 is used so as to cause the discharge mechanism to go back to its initial position, whereupon the slotted portion thereof, or open portion thereof, is adapted to receive the next bottle, when and as the pressure applied by

the hand of the user to rotate the discharging member is released.

As a result of such movement of the lowermost bottle, the remaining bottles in each section, as is more clearly shown in the cutout cross-sectional view of Figure 1, are caused to be downwardly and angularly displaced in the tortuous path, to the extent of the prescribed distance, until one bottle rests against the other contained within the discharging shell (see the right hand side of Figure 5), it being obvious that as the discharging shell in the right hand side of Figure 5 is rotated to the left, that the bottle resting thereabove and adjacent will be pressed upwardly and away from the free curved edge of the discharging shell, and will rest against the upper surface of the same as it is rotated (see Figure 5, left hand side).

Because of their relative arrangements and curvatures, the staggered series of horizontally elongated guide projections or sections 20 form excellent means for slowly lowering the bottles, without breakage, when the empty or partly empty chamber is being filled. It is understood that this is due in part to the fact that the upper 100 guide face 21 of each section or projection 20 is concaved substantially on a longitudinal axis, to somewhat approximate the curvature of the bottle, gradually curving from approximately vertical at the upper part of said face to approximately horizontal at its lower margin, thereby to exert centripetal force upon, and firmly engage, the bottle when rolling down said face, to give the bottle a spinning movement and project it to the opposite side of the chamber, in such a path 110 that the adjacent lower and upper guide faces of adjacent projections 20 on the opposite side of the chamber are so curved and positioned as to receive the projected bottle substantially tangentially of the path of the bottle, whereby the 115 bottle is first lightly engaged, without shock, and then centripetally pressed and therefore firmly engaged and turned back across the passage, the bottle at the same time being thereby rotated in the opposite direction and thereby frictionally 120 slowed in its movement, and again projected, as above stated.

It is obvious that various changes and modifications may be made to the details of construction without departing from the general spirit of 125 the invention as set forth in the appended claims.

We claim:

1. A bottle dispensing device comprising in combination a casing having vertically disposed walls which provide a space therebetween, spaced 130 curved guides carried by one of said walls and having projections in said first space, spaced curved guides carried by the opposite wall and having projections disposed between said first projections whereby to provide a zigzag path for 135 a downwardly moving bottle, and upwardly disposed ribs carried by said projections for retarding the downward movement of the bottle by revolving the latter in opposite directions.

2. In combination, means forming an upright 140 passage chamber for bottles and the like, said chamber having its opposite sides respectively formed with staggered series of guide projections having upper guide faces respectively; and means adapted to give to the bottle an upward movement as it leaves each guide face and project it to the adjacent upper guide face on the opposite side of the chamber.

3. In combination, means forming an upright 145 passage chamber for bottles and the like, said

chamber having its opposite sides respectively formed with staggered series of guide projections having upper guide faces respectively; each provided at its discharge edge, with a projection adapted to engage a bottle to give it an upward movement and project it to the adjacent guide face on the opposite side of the chamber.

4. In combination, means forming an upright passage chamber for bottles and the like, said chamber having its opposite sides respectively formed with staggered series of guide projections having upper guide faces respectively; the upper guide face of each projection being concaved and provided, at its discharge edge, with an upwardly and outwardly inclined projection adapted to engage, a bottle rolling down said face, to give it an upward movement as it projects to the adjacent upper guide face on the opposite side of the chamber, thereby to retard the fall 20 of the bottle by said upward movements.

5. In a storage and vending method, method steps which comprise initially dropping one-by-one a plurality of axially horizontal bottles into an upright space; stopping the first bottle at a lower part of said space, whereby each subsequent bottle is brought to rest on its side by striking on the side of the preceding bottle; causing each bottle to move slightly upwardly at frequent points all along said space, thereby limiting the downward velocity and acceleration of the bottles to low maxima near the upper part of the space, said maxima being sufficiently low to prevent breakage from said striking; said points being sufficiently close together to maintain the downward velocity and acceleration as low as 90 said maxima throughout the whole of said space and fall, whereby breakage is prevented no matter how far the bottles may travel in the space.
